UNITED STATES PATENT OFFICE.

RICHARD JAMES EDWARDS, OF GALENA, ILLINOIS, ASSIGNOR OF ONE-FOURTH TO FERDINAND HENGESCH, OF CHICAGO, ILLINOIS.

SPRING-BEARING FOR VEHICLES.

No. 873,221.

Specification of Letters Patent.

Patented Dec. 10, 1907.

Application filed May 15, 1907. Serial No. 373,802.

To all whom it may concern:

Be it known that I, RICHARD JAMES EDWARDS, of Galena, in the county of Jo Daviess and State of Illinois, have invented 5 certain new and useful Improvements in Spring-Bearings for Vehicles; and I do hereby declare the following to be a full, clear, and exact description of the invention, such as will enable others skilled in the art to 10 which it appertains to make and use the same.

My invention relates to an improvement in spring bearings for vehicles, is designed more particularly as an improvement on the 15 construction disclosed in my patent No. 843,591 granted February 12th, 1907, and it consists in the parts and combinations of parts and in the details of construction as will be more fully explained and pointed out 20 in the claims.

In the accompanying drawings, Figure 1 is a view in vertical longitudinal section of my improved sectional bearing with the springs therein, the latter being shown in 25 elevation. Fig. 2 is a view in transverse vertical section of same. Fig. 3 is a view in plan of the lower section of the bearing and Fig. 4 is a view in transverse section of same taken through one of the spring supporting 30 studs.

1 represents the upper and 2 the lower sections of the bearing or casing in which a series of carrying springs 3 are mounted. These sections are preferably rectangular in 35 shape, with slightly rounded corners, the upper section 1 being somewhat longer and wider than the lower section 2 so as to embrace the upper end of the lower section, sufficient clearance being left, as clearly 40 shown in Figs. 1 and 2, to permit a free vertical movement, and a slight rocking movement of the upper section without binding on the lower section.

The lower section 2 is provided at its ends 45 with vertical slots 3' in which the screw pins 4 rest and move. These pins are screwed into the ends of the upper section of the casing, near the lower edge of the latter, and project into the slots 3', the pins being 50 smaller than the slots, so as to prevent the upward displacement of the upper section, without interfering with its ordinary movements.

Each section 1 and 2 is provided centrally 55 with a series, (in the present instance five) of

integral cylindrical studs 5 which form end supports and seats for the springs 3, the studs in the upper section corresponding in position with those of the lower section, so that when the casing sections and springs 60 are assembled, the studs supporting one spring are in pairs, the studs of each pair being in the same vertical plane. Each stud is about one third the normal interior height of the casing, thus leaving about one third of 65 each spring free. When however the upper section 1 is moved downwardly, the entire spring will be compressed, the studs 5 simply operating as supports for the springs and preventing them from lateral deflection, and also 70 to limit the collapsing movement of the bearing.

The closed lower face of the bottom section 2, and the closed upper face of the top section 1 are recessed on their inner surfaces 75 as at 7, at the side of each stud 5, to receive the loop shaped ends 8 of the springs 3, which loop shaped ends are secured within the recesses 7 by the screws 9, which as shown in Fig. 2, securely hold the ends of 80 the springs against displacement.

By removing either the upper or lower set of screws 9, and the end screws 4, the sections 1 and 2 of the bearing or casing may be separated for repairing or replacing any of 85 the springs.

The upper section 1 of the casing is provided at its top with integral side flanges 10 having holes for the passage of screw or bolts for securing the bearing to the underframe 90 or body of a motor or other vehicle, and the lower section 2 is provided with similar flanges 11 to which the wood spacing block 12 which may vary in thickness, and the metal clip 13 are secured by the bolts and 95 nuts 14. The clip 13, is shaped centrally as at 15 to receive an axle. In the present instance I have shown it shaped to receive an angular axle, the under side of the wood spacing block 12 being cut away to receive 100 the curved top, but it should be understood that the shape of the part 15 of clip 13, will be dependent altogether upon the shape of the axle it is to receive. I have also shown the lower face of the bottom of section 2 recessed at 16 to receive a king bolt head. This recess 16 would only be needed where the springs are used on vehicles other 105 than motor vehicles.

In the drawings I have shown the bearing 110

arranged to be mounted at right angles to the axle, but it is clearly evident that it can be mounted on an axle with its long diameter in the direction of the length of the bolster, or axle as there are no projecting movable rods to interfere, as in my patented bearing previously referred to, or it can be mounted lengthwise the front buggy bolster with the head of the king bolt in the recess 16.

10. By providing the lower section 2 of the bearing with slots 3' in which the pins 4 move, any dust or dirt entering the bearing may work out or be worked out through these slots without disconnecting any parts.

15. It is evident that many slight changes might be resorted to in the relative arrangement of parts herein shown and described without departing from the spirit and scope of my invention hence I would have it understood that I do not wish to confine myself to the exact construction of parts shown and described, but,

20. Having fully described my invention what I claim as new and desire to secure by Letters-Patent, is:—

1. In a spring bearing for vehicles, the combination with a two part hollow casing, the open bottom of the top part overlapping the open top of the lower part, and screw pins carried by one part and resting within slots in the other part, of springs within the two part casing, the said springs having looped ends resting in recesses in the top and bottom of the casing and screw bolts passing through said looped ends.

2. In a spring bearing for vehicles, the combination with a two part casing, the open bottom of the top part overlapping the open top of the lower part, each part of the casing

having projecting studs arranged in pairs and 40 forming seats for the springs, and screw bolts carried by the top part and moving in slots in the lower part, of coiled springs each seated on a pair of studs, the ends of each spring being looped and resting in recesses adjacent 45 to the bases of the studs, and screw bolts passing through said looped ends.

3. The combination with a two part hollow casing the upper part overlapping the lower part, each provided with horizontally 50 projecting flanges for attachment to the vehicle, and each provided internally with a series of vertical studs, the latter being arranged in pairs, of a coiled spring for each pair of studs, the said springs having looped 55 ends resting in recesses adjacent to the bases of the studs, and bolts passing through said looped ends.

4. The combination of the upper and lower overlapping sections of the casing, each section having a series of integral studs, and recesses adjacent to the bases of the studs, springs, each seated at its ends on a pair of studs and provided with looped ends resting in said recesses, bolts passing through said 65 looped ends, a wood spacing block under the lower section of the casing and a clip for securing the casing to the bolster or under-frame of the vehicle, the said lower section of the casing, spacing block and clip being secured together, substantially as described.

In testimony whereof, I have signed this specification in the presence of two subscribing witnesses.

RICHARD JAMES EDWARDS.
